UNITED STATES PATENT OFFICE

2,257,990

SWITCH

Wilfred J. Turenne, Fayville, Mass.

Application January 29, 1940, Serial No. 316,069

5 Claims. (Cl. 200—137)

This invention, which is an improvement on the apparatus disclosed in United States Letters Patent No. 2,090,407, August 17, 1937, and No. 2,185,433, January 2, 1940, relates to thermostatic switches, and the object thereof, generally stated, is to improve the switches shown in said Letters Patent in the manner hereinafter more fully set forth.

Experience has shown that there is sometimes a tendency to distortion of the circuit-controlling metal strips when the switch, after a period of use to maintain a relatively high temperature (such as 400° F.), is cooled to a much lower temperature. This is due to the fact that both ends of the circuit-controlling member are rigidly connected to its supports in the switches disclosed in said patents and in other prior patents. The difficulty is overcome by rigidly securing the circuit-controlling member at one end only and connecting it at the other end slidably to an abutment member, the arrangement being such that by manually operable adjusting means in co-operative engagement with said circuit-controlling member and the casing or other means whereby the circuit-controlling member is supported, there is effected relative movement between the abutment member and the circuit-controlling member as a whole. It has been found also that the means for guiding that head of the circuit-controlling member to which the switch adjusting means is attached is not at times wholly satisfactory, for the reason that the relative movement between said head and the casing is not always rectilinear. The means disclosed in the later of the two patents aforesaid are a pair of oppositely disposed V-shaped ribs formed in the inner wall of the casing and taking into correspondingly shaped notches formed in one of the heads of the circuit-controlling member. This difficulty is overcome by making the ribs and notches substantially rectangular, whereby the axial movement of the notched head with respect to the casing is always a straight line movement whereby the axis of the circuit-controlling member is maintained at all times coincident with the axis of the casing.

The means for adjusting the switch for opening or closing the circuit controlled at a predetermined temperature heretofore comprised two members threaded, respectively, interiorly and exteriorly, and the arrangement was such that only a portion of the threads of the interiorly threaded member, which having been cut with a tap are accurate, engaged the threads of the exteriorly threaded member, which, having been

cut with a die, were not consistent throughout their entire length. This sometimes made it difficult accurately to adjust the switch to function at preselected temperatures. This difficulty has been overcome by threading the interiorly threaded member throughout its length, and the exteriorly threaded member only a portion of its length, so that the threads of the interiorly threaded member or sleeve engage all of the threads of the exteriorly threaded member or stud for every adjustment of the circuit-controlling member throughout the range of operation of the switch.

In the accompanying drawing, Figure 1 is a longitudinal section of a thermostatic switch embodying the present invention.

Figs. 2 and 3 are elevations on an enlarged scale of details of construction.

Fig. 4 is a transverse section taken on the line 20 4—4 of Fig. 1.

Fig. 5 is a top view of the switch shown in Fig. 1.

Fig. 6 is a fragmentary sectional view on an enlarged scale, somewhat diagrammatic in form, and illustrating a constructional procedure.

Fig. 7 is an elevation partly in section illustrating a modified form of a detail shown in Fig. 1.

In the particular drawing selected for illustrating the principle underlying the invention, such drawing being illustrative only and not restrictive, 10 is a casing, herein shown as tubular, formed of a material having a relatively high coefficient of expansion such, for example, as brass, 30 in which is disposed the circuit-controlling member 11, herein shown as a pair of bowed metallic leaf springs 12 formed of a metal having a relatively low coefficient of expansion, such for example, as invar, or other suitable metal whose coefficient of expansion is practically nil. While the spring members 12, 12, are shown in the present instance as bowed inwardly, it is to be understood, of course, that they may be bowed outwardly with their concave sides opposed, as shown in Patent No. 2,185,433. In either case, each spring is provided with a suitable electric contact 13 secured thereto at the central portion thereof and insulated therefrom by insulating material indicated at 14.

The circuit controlling members 12, 12, are provided with heads 15, 16, rigidly secured thereto at the respective ends thereof. The head 15 comprises the flanged disc 15a, two opposing sides of which are cut away or slotted to receive the spring members 12, 12, and the clamping disc

15b between which two discs, the bent over ends of said spring members, are disposed. The head 16 consists of the flanged disc 16a and clamping disc 16b between which the other ends of the spring members are placed. It is to be understood, however, that any suitable means, such as those shown in either of the prior patents aforesaid, may be used for the heads of the circuit-controlling member and that they may be rigidly secured thereto by welding or in any other suitable manner.

For adjusting the switch, a variety of means may be employed. In the embodiment of the invention shown in Fig. 1, such means comprises the stud 17 rigidly connected at its inner end to the head 15 and threaded at its outer end, the threaded end preferably being slit, as shown at 18, to increase the resiliency thereof and strengthen the grip of its threads on those of its co-operating member which consists of an interiorly and exteriorly threaded sleeve 19, the interior threads whereof are in engagement with those of said stud and the exterior threads with those of the threaded bore through the disc 20 which forms one of the end closures of the casing. It will be understood, of course, that the threads of the stud have a higher pitch than the exterior threads of the sleeve.

Surrounding the stud and secured to the end closure 20 is a tubular shield 21, shown in the present instance as having one end disposed within the counterbored part of the threaded bore passing through said end closure and its inner end spaced away from the flanged disc 15.

Rigidly secured as by welding or soldering to the end closure 22 of the casing is a rod 23 passing through and loosely engaging the head 16, said rod having a flange 24 at its inner end and provided with fins 25 spaced away from the outer end of the head aforesaid when the inner end thereof abuts said flange.

The flanged rod 23 constitutes an abutment member for transmitting to the circuit-controlling member the stress created by the expansion of the casing.

Insulated conductors 26, 28, from the heating unit or other device to be controlled, enter the switch through the closure 20 and are electrically connected to the electric contact members 13, 13, in any suitable manner, as indicated at 27, 27. Preferably, each of said conductors is wrapped once or twice around the shield 21 to anchor them in position.

A portion of the inner wall of the casing intermediate its ends preferably is covered with insulating material, as indicated at 28, and insulating discs 28' may be placed in the end of the casing to which the rod 23 is attached.

Means are provided to prevent relative rotational movement between the head 15 and the casing during the adjustment of the switch. The means shown in the drawing for attaining this result consist in a pair of oppositely disposed substantially rectangular ribs 29 formed in the wall of the casing and taking into a pair of correspondingly shaped notches 30 milled out of the face of the flanged disc 15a. The said ribs must be rectangular to effect the desired result and they must be formed on the inner face of the shell, for it would not be practicable to weld ribs or keys on such inner wall. Heretofore it has been attempted to form one guide rib or a pair thereof by pressing them inwardly by a tool applied to the outer wall of the casing, as indicated in the patents above referred to. Such ribs so

formed, which were V-shaped, however, were not wholly satisfactory and much better results are obtained by the substantially rectangular ribs and co-operating notches shown herein. Not only must said ribs be integral with the casing, but they can only extend inwardly from the inner wall thereof for but a limited distance on account of the bulk of the insulated conductors. For this reason the ribs must be of substantial width. A rib formed on the inner wall of a tubular member of soft metal, such as brass, by a blow from a tool applied to the outer wall will, in general, be curvilinear and not rectangular and would therefore be useless for the double purpose of preventing relative rotational movement between the head 15 and the casing during the adjustment of the switch and insuring a straight line movement of the circuit-controlling member longitudinally of the casing during such adjustment whereby the axis of said member is maintained at all times coincident with the axis of the casing.

After much experimentation it was found that a substantially rectangular rib could be produced in the following manner:

A square ended tool 31 is placed radially against the outer face of the casing and sufficient force applied to produce an inwardly extending rib which, as aforesaid, will have rounded corners, as indicated in dotted lines at 32a, 32b, the general conformation of the groove so formed in the outer wall of the casing being indicated in dotted lines at 33a, 33b. The casing is then rotated a few degrees in a clockwise direction substantially about the axis 34 of said groove and the tool placed substantially in the position indicated in dotted lines at 31a against the inner wall of said groove, indicated at 33a, and then upon the application of suitable force thereto, the rounded corner 32a is forced inwardly so that said corner becomes substantially square. The casing is then rotated a few degrees in a counterclockwise direction about said axis 34 and the tool placed in the position 31b against the wall 33b of the groove, whereupon by the application of suitable force the curved corner 32b is pushed inwardly and becomes substantially square.

The operation of the improved switch herein described will be readily understood by those skilled in the art by the disclosures of the above mentioned patents.

When the switch is maintaining any temperature within its range for which it has been adjusted, the head 16 is, as shown in Fig. 1, in engagement with the flange 24, the latter having been drawn thereagainst by the expansion of the casing. When the adjustment is for a relatively high temperature, the longitudinal expansion of the casing required to separate the contacts 13, 13, is of course greater than when the switch is adjusted for a substantially lower temperature. Should the switch, after having been used to maintain such relatively high temperature, be brought, within a comparatively short period of time, to a much lower temperature, as frequently occurs in practice, the stress to which the leaf springs would be subjected were both ends of the circuit-controlling member rigidly secured to its supports, as in the case of the prior patents, would distort said springs so that thereafter the switch would not function properly. In the case of the present invention, however, the sliding connection between the head 16 and abutment member 23 will permit the latter to

move inwardly without exerting any longitudinal pressure whatever upon the springs.

Another advantage residing in the loose or sliding connection of the head 16 with said abutment member is the ease with which the threaded sleeve 18 can be reinserted should it, by design or accident, have been completely removed from the switch. In such case, it is possible that upon reengaging said sleeve with the threads of the stud 17 and the threads of the closure 20, the contacts of the circuit-controlling member will be separated before the sleeve has engaged more than three or four of the threads of said closure, and this possibility would be enhanced if the lower head were rigidly secured to the rod 23. With the present invention, however, it suffices, in such situation, to back the sleeve sufficiently to disengage the exterior threads thereof with those of the closure 20 and then give it, say, one additional turn, so that the inner end thereof is positioned a short distance outwardly of the outer face of said closure. Thereupon, the threaded end of the stud 17, being still in engagement with the interior threads of the sleeve, the user can then push the sleeve and stud and the circuit-controlling member inwardly, the head 16 being slidably connected with the rod 23, until the exterior threads of said sleeve are in position to engage the threads of the closure 20, whereupon it will be possible to give the sleeve a number of turns before the electrical contacts separate.

There is a third advantage in the sliding connection of one of the heads of the circuit-controlling member with its circuit, viz.—in the switch of Patent No. 2,090,407, the lower head of which is rigidly secured to its support, it is somewhat difficult to engage the threads of the adjusting screw with those of the cylinder head and with those of the circuit-controlling member head and have a sufficient number of threads in engagement to permit of the adjustment of the switch for all temperatures within its range. In that switch the threads of the adjusting screw were first engaged with those of the head of the circuit-controlling member and then the upper threaded end of said screw engaged with the threads of the cylinder head. As will be obvious, it would be necessary at times to exert undue pressure on the circuit-controlling member and distort the springs thereof in order to engage the threads on the upper end of the adjusting screw with the threads of the cylinder head, and it was frequently found that even after exerting such pressure on the circuit-controlling member, an insufficient number of the threads on the upper end of the adjusting screw were in engagement with the threads of the cylinder head to enable all adjustments within the temperature range of the switch to be obtained.

In the present invention, as will be manifest, the loose connection of the head 16 with the rod 23 eliminates any necessity for exerting pressure on the leaf springs in order to engage the threaded sleeve sufficiently for any required temperature adjustment. It will be obvious that the foregoing advantages apply equally well to the switch shown in Patent No. 2,185,433, aforesaid.

As above noted, another feature of the present invention which eliminates any possibility of distortion of the leaf springs is the substantially rectangular rib and notch arrangement above described and such arrangement, although it may be used with advantage in the structures dis-

closed in either of the prior patents aforesaid, is particularly advantageous in the case of the present invention for the reason that by virtue of the sliding connection of the head 16 with its supporting member, the relative movement between the circuit-controlling member and the casing necessarily is greater than in the structures of said patents.

A feature found by practice to be of great importance in the present case is the arrangement whereby the interior threads of the sleeve 18 are in engagement with all of the threads of the stud for every adjustment of the circuit-controlling member throughout the range of operation of the switch. It is to be understood, of course, that the pitch of the exterior threads of the sleeve is somewhat lower than that of the interior threads thereof in order to obtain the necessary differential action for accurate adjustment. The interior threads of the sleeve having been tap-cut and therefore accurate throughout their entire length, are for every adjustment of the circuit-controlling member in engagement with all of the threads of the stud which, being die-cut, can never be absolutely accurate throughout the length of the threaded portion of said stud. Thus, such inequality or irregularity in the exterior threads of the stud 17 is equalized or compensated for and thereby the accuracy of adjustment is greatly enhanced in sharp contradistinction to the arrangement of the prior art, referring to Patent No. 2,185,433, for example, wherein the accurately cut interior threads of the sleeve are in engagement with only a relatively small number of the necessarily somewhat inaccurately cut exterior threads of the stud, which results in unequal longitudinal movement of the stud per turn of the sleeve, such movement varying with the location on the stud of the threads thereof which are in engagement with the threads of the sleeve. It is not necessary in order to effect the improvements above recited that the head 16 should be in loose engagement with its supporting member, for said head may be rigidly secured to the rod 23 and, as shown in Fig. 7, the head 16 arranged for limited sliding movement over the unthreaded end of the stud 17.

In the present instance this is done by notching the sleeve portion of the disc 16a, as indicated at 35, and driving a pin 38 through a hole in said stud, such pin passing through said notch and affording a means for restraining relative rotational movement between the stud and head and also constituting an abutment member for transmitting to the circuit-controlling member 11 the stress created by the expansion of the casing 10. In Fig. 7 the bottom of the notch is shown out of contact with said pin, but it will be understood, of course, that when the switch is maintaining any given temperature for which it has been adjusted, the pin is in engagement with the bottom of said notch, just as in the case of the switch shown in Fig. 1, the sleeve, which is integral with the disc 16a, is always in engagement with the flange 24 when the switch is maintaining any temperature for which it is in adjustment.

The rod 23 preferably is formed of invar, or any other substantially non-expansive alloy, and if desired, the stud 17 may be formed of such material for extreme accuracy.

Having thus described illustrative embodiments of my invention without, however, limiting the

same thereto, what I claim and desire to secure by Letters Patent is:

1. A thermostatic switch comprising a casing of material having a relatively high coefficient of expansion, said casing having a threaded bore at one end and an abutment member rigidly secured to and extending inwardly of the other end thereof, a circuit-controlling member of material having a relatively low coefficient of expansion disposed within said casing, a head secured to one end of said circuit-controlling member, means for adjusting the longitudinal position of said circuit-controlling member, said means having a threaded stud secured to said head, and an interiorly and exteriorly threaded sleeve, the interior threads whereof are in engagement with said threaded stud and the exterior threads, with said threaded bore, and a second head rigidly secured to the other end of said circuit-controlling member and slidably connected to said abutment member.

2. A thermostatic switch comprising a casing of material having a relatively high coefficient of expansion, said casing having a threaded bore at one end and an abutment member rigidly secured to and extending inwardly of the other end thereof, a circuit-controlling member of material having a relatively low coefficient of expansion disposed within said casing, a head secured to one end of said circuit-controlling member, means for adjusting the longitudinal position of said circuit-controlling member, said means having a threaded stud secured to said head, and an interiorly and exteriorly threaded sleeve, the interior threads whereof are in engagement with all of the threads of said stud for every adjustment of said circuit-controlling member throughout the range of said switch, and the exterior threads whereof are in engagement with the threads of said bore, and a second head rigidly secured to the other end of said circuit-controlling member and slidably connected to said abutment member.

3. A thermostatic switch comprising a casing of material having a relatively high coefficient of

expansion, a circuit-controlling member of material having a relatively low coefficient of expansion disposed therein, heads rigidly secured to the respective ends of said circuit-controlling member, and means for adjusting said circuit-controlling member to maintain any temperature within the range of the switch, one of said heads being provided with two oppositely disposed substantially rectangular notches and the inner wall of said casing having two substantially rectangular ribs co-operating, respectively, with said notches.

4. A thermostatic switch comprising a casing, a circuit-controlling member enclosed therein, means for adjusting said circuit-controlling member to maintain any temperature within the range of the switch, heads rigidly secured to the respective ends of said circuit-controlling member and abutment means loosely engaging one of said heads, said abutment means being movable with respect to such head for transmitting to said circuit-controlling member the stress created by the expansion of said casing and being independent of said adjusting means.

5. A thermostatic switch comprising a casing of material having a relatively high coefficient of expansion, a circuit-controlling member of material having a relatively low coefficient of expansion disposed in said casing, heads rigidly secured to the respective ends of said circuit-controlling member, a threaded stud passing through and having loose engagement with one of said heads, means rigidly connected to said stud and having relative longitudinal movement with respect to the head through which said stud passes for restraining relative rotational movement between said stud and such head, said means constituting an abutment member for transmitting to said circuit-controlling member the stress created by the expansion of said casing, and manually operable means in co-operative engagement with said casing and said stud for effecting relative movement between said stud and said circuit-controlling member.

WILFRED J. TURENNE.
